(57) CLAIM

The ornamental design for a shoe, as shown and described.

DESCRIPTION

FIG. 1 is a front perspective view of a shoe showing my new design;

FIG. 2 is a side view thereof;

FIG. 3 is an opposite side view thereof; and,

FIG. 4 is an opposite side front perspective view thereof. The broken lines within the photographic area represent screws that form no part of the claimed design. The broken lines depicting the remainder of the shoe form no part of the claimed design.
